Primary Examiner—M. N. Pandozzi

(74) Attorney, Agent, or Firm—Dorsey & Whitney LLP

(57) **CLAIM**

I claim the ornamental design for beer keg nozzle cover, as shown.

DESCRIPTION

FIG. 1 is an isometric-looking downwardly at the front of the beer keg nozzle cover of the present invention.

FIG. 2 is an isometric-looking downwardly on the rear of the beer keg nozzle cover of FIG. 1.

FIG. 3 is a top plan view of the beer keg nozzle cover.

FIG. 4 is a left side elevation of the beer keg nozzle cover.

FIG. 5 is a front elevation of the beer keg nozzle cover; and,

FIG. 6 is a bottom plan view of the beer keg nozzle cover.
